UNITED STATES PATENT OFFICE.

WILLIAM A. CUSHMAN, OF PROVIDENCE, RHODE ISLAND.

IRON RAILWAY-CAR.

SPECIFICATION forming part of Letters Patent No. 243,762, dated July 5, 1881.

Application filed May 19, 1881. (No model.)

To all whom it may concern:

Be it known that I, WILLIAM A. CUSHMAN, of Providence, in the State of Rhode Island, have invented an Improvement in Tubular Iron Railway-Cars, of which the following is a specification.

In Letters Patent No. 236,786 an iron platform for cars is shown with tubes that are united by bands, and there are braces of iron 10 passing down beneath a cross-bearer below the tubes, and in an allowed application the transom-beam and end beam are made of angle or L iron and the tubes united by hubs.

My present invention is an improvement 15 upon the aforesaid invention, and relates to a means for clamping the tubes very firmly, so as to prevent the bands slipping or becoming loose upon the tubes; also, to the manner of attaching the ends of the tubes to the end bearers, and to the manner of forming the transom-beam and of constructing the cross-bearer for the diagonal braces.

In the drawings, Figure 1 is a longitudinal elevation of part of the platform, the tubes at 25 the ends being in section. Fig. 2 is a cross-section at the line x x. Fig. 3 is an elevation, in larger size, of the clamping-band; and Fig. 4 is a view of clamp at right angles to Fig. 3.

There are to be two tubes, a a, one above 30 the other, extending from end to end of the platform, and such a pair of tubes is placed at each side of the platform, and as many intermediate ranges as may be necessary for obtaining the desired strength. Usually there will be six pairs of these tubes. At the ends of the 35 platform the tubes are to be united to angle-iron sills b by the hubs, as in my aforesaid application, or in any other convenient manner. I have shown sockets c c with internal screw-40 threads to receive within them the threaded ends of the tubes, and these sockets are to be of malleable iron or other metal and provided with bolts or rivets d, passing through the end sill, b, and secured by nuts. This mode of 45 construction allows the parts to be put together with great facility, and by providing a L-shaped sill with the flanges outwardly a recess is formed for the reception of the projecting

safety-blocks f, which are to be of wood or other material.

The transom-beam is preferably made of two L-shaped bars, h, that pass transversely between the tubes a a, and are set back to back and bolted to the clip-bands, and these transverse beams receive the center plates for the 55 king-bolts of the trucks.

One of my special features of improvement relates to the malleable-iron or steel clips i i, formed of two short cylinders, 3 3, at the ends of and connected by a bar, 4, and the cylinders and bar are formed with forks or splits at 5, through which pass the transverse bolts l. The cylinders 3 3 are of a size that allows them to be slipped over the tubes to the proper places, after which the bolts l are screwed up so firmly 60 as to partially close the splits and clamp the tubes in the most firm and reliable manner. The bar 4, at the middle portion, may be X-shaped sectionally, or of any other desired form, so as to possess the requisite strength and lightness.

The diagonal braces m pass from the end sills over the transom-beams and beneath a cross-beam, n, below the tubes a. This may be similar to that shown in my aforesaid patent; 75 but I prefer and use a cross-bearer of metal at the lower ends of downwardly-extending struts p, which are prolongations of the clips i i, and preferably of the same metal, and each cross-bearer n is made of a metal tube passed into 80 the lower ends of the said struts p, into which it may be secured by wedges, cross-pins, or by being screwed into the cylinders 6 of the struts. There may be two, three, or more of these longitudinal diagonal braces in the car-platform. 85

I claim as my invention—

1. The combination, with the longitudinal iron tubes in a car-platform, of the clips i i, having cylindrical ends for the reception of the tubes a a, and forked or split, and the bolts l 90 to tighten the clamps upon the tubes, substantially as set forth.

2. In a car-platform, the clips i i and the struts p, in combination with the tubes a a and the cross-bearer n and braces m, substantially 95 as set forth.

3. In a car-platform, the combination, with
the metal tubes *a*, clips *i*, and struts *p*, of the
cross bearing-tube *n* and braces *m*, substan-
tially as set forth.
- 5 4. The combination, in a car-platform, of
the longitudinal tubes *a a*, the L-shaped bars
h, set back to back, forming the transom-beam,
and the clips *i i*, that connect the tubes *a a*,
substantially as set forth.

Signed by me this 11th day of May, A. D. 10
1881.

WM. A. CUSHMAN.
